UNITED STATES PATENT OFFICE.

GEORGE R. PERRY, OF WASHINGTON, DISTRICT OF COLUMBIA.

KEY HOLDER.

1,423,147.

Specification of Letters Patent. Patented July 18, 1922.

Application filed February 28, 1921. Serial No. 448,552.

To all whom it may concern:

Be it known that I, GEORGE R. PERRY, a citizen of the United States, residing at Washington, in the District of Columbia, have invented certain new and useful Improvements in Key Holders; and I do hereby declare the following to be a full, clear, and exact description of the invention, such as will enable others skilled in the art to 10 which it appertains to make and use the same.

This invention relates to key holders, and more particularly to a combined key holder and coin container with identifying means 15 to facilitate its return to the owner when lost. The object of the invention is to provide a simple, efficient and inexpensive device of the character referred to having means associated therewith for holding keys or bunches of keys in separated relation, together with means for rewarding and thereby inducing the finder of a lost key holder to return the same to the owner; a suitable reward being enclosed within the holder together with instructions for returning the device to the owner.

The invention will first be hereinafter more particularly described, with reference to the accompanying drawings, which are 30 to be taken as a part of this specification, and then pointed out in the claims at the end of the description.

In said drawings,

Fig. 1 represents a side elevation of a key holder embodying my invention;

Fig. 2 is a similar view looking at the opposite side of the device;

Fig. 3 is an end or edge view thereof;

Fig. 4 is a transverse sectional view taken 40 on the line 4—4 of Fig. 2;

Fig. 5 represents in side elevation the two disk-like members of the key holder taken apart, and looking at the inner sides thereof, to expose to view means within and detachably secured to one of said members for attaching keys thereto, with capacity for holding a coin normally concealed therein to serve as a reward and inducement to the finder of the device when lost to return it 45 to its rightful owner, in accordance with instructions also contained within the holder;

Fig. 6 represents a side elevation of a combined key holder and coin container embodying a modified form of my invention;

Fig. 7 is a similar view of said modified form of the device looking at the opposite side thereof;

Fig. 8 is an end or edge view of said modification;

Fig. 9 is a transverse sectional view taken on the line 9—9 of Fig. 7; and

Fig. 10 represents in side elevation the two disk members taken apart, looking at the inner sides thereof.

Referring to said drawings, in which the same reference letters are used to denote corresponding parts in different views, the letters A and B denote disk-like members of a key holder and coin container, each having a peripheral flange, denoted by the letters *a*, and *b*, respectively, one of which flanges is adapted to fit closely within the other for holding the two parts together, so as to provide a coin container or case 75 within which may be placed a coin, or device to be redeemed, of any desired value, for example a quarter of a dollar, or its equivalent; said case having combined therewith means for securing thereto a key or keys, 80 either singly or collectively, in one or more bunches, with individual keys or bunches arranged in separated relation. The two members A and B are preferably of annular form, with annular overlapping flanges, 85 though other forms may be employed, said flanges being adapted to fit snugly one within the other so that they will be held together by frictional contact and may not easily come apart or be separated without 90 applying force as hereinafter described. However, other forms and other securing means may be employed without departing from the spirit and scope of my invention.

The peripheral flanges *a* and *b* are formed 95 or provided with co-incident open-ended slots or notches *a*¹ and *b*¹ to provide openings through which loops or eyes *c* project from a spring *C*, seated within one member at the base of its peripheral flange; said 100 eyes being adapted to receive links of a chain or chains or a key or key ring for attaching thereto a key or keys, or a chain or chains on which may be secured a key or keys or bunches of keys in such manner 105 that individual keys or bunches may be held in separated relation for convenient handling and to enable the owner by the sense of touch or location on the holder to pick out a particular key in the dark with- 110

out the aid of a light. The spring C is made of spring steel wire or other resilient material and is held on the inner side of the smaller member B of the holder by 5 means of flaps b^2 which are formed by cutting the marginal flange b and bending the cut portions inwardly over the ends and intermediate portion of the spring, which fits closely against the inner side of the 10 member B at the base of said marginal flange, with its eyes or loops projecting through the open-ended slots, as shown. Either end of the spring may be sprung out from underneath its retaining flap, to 15 permit the link of a chain or a key ring to be slid thereon into engagement with an eye or loop c , whereupon the released end may be snapped back into place under the flap by which it is held to its work. As 20 shown, the spring has two eyes or loops c , formed thereon, but may have a greater or less number, and a corresponding number of openings may be provided therefor through the periphery of the case or key 25 holder. Two or more flaps b^2 intermediate the end flaps may be provided to more securely fasten the spring within the retaining member of the holder and prevent accidental displacement when either end 30 thereof is disconnected from the end flap, though one intermediate flap will suffice. In assembling, the spring C is placed within the annular member of the holder, at the base of its marginal flange, and secured 35 by turning the cut portions of the flange which form the flaps b^2 inwardly over the ends of the spring and the intermediate portion thereof, preferably between the eyes or loops which project through the 40 open-ended slots in the periphery of the flange of the retaining member. A bunch of keys, as at D, may then be connected with one eye or loop and a night key E with another eye or loop, the latter key being 45 held apart from the other keys so that it can be easily selected from a bunch of keys by sense of touch in the dark. There may also be placed conveniently within the holder a label or tag having inscribed or 50 printed thereon the name and address of the owner or the owner's registration number and suitable directions or instructions to enable the finder to return the lost article to the owner through the mails, or by leaving it for delivery to the owner at a local bank or other depository where the owner is registered. The other annular member is 55 then placed with its flange a overlapping the flange b of the member B and pressed 60 tightly thereon, thus securing them together. On one side of the case may be inscribed or impressed the name and address of a local bank or other depository where the owner is registered, for example, 65 the words "Owner registered at the Dollar

Savings Bank, Youngstown, Ohio," or other words. On the other side of the holder may be inscribed or impressed instructions as to how to open the holder and what to do with it, in order that it may be returned 70 to the rightful owner; for example, in rainbow form around the upper half of the case the words "Insert knife blade in peripheral slot and pry open", and below such words the following, "Finder please open 75 this holder, comply with instructions herein and receive reward." The tag enclosed within the case may bear on one side thereof the registration number of the owner, which may be seen through an oblong slot 80 a^2 in the case member A, so that when returned to the bank the name of the owner may be ascertained by reference to the corresponding registration number on the books without opening the case. 85

In Figs. 6 to 10 is shown a modification of my invention, in which the case members A¹ and B¹ are constructed in substantially the same manner as the case-members A and B of the key holder shown in Figs. 1 to 90 5, but without the notches or open-ended slots in the marginal flanges and omitting the spring and associated parts for connecting thereto a key or keys. Otherwise the device is essentially of the same construction as the key holder hereinbefore described, but instead of the spring for attaching a key or keys thereto the outer case member has secured thereto one or more eyes a^3 which may be connected by a chain 100 having a snap-hook at one end for attaching a key or keys. It is adapted to contain a coin or coins and a tag with instructions thereon the same as described with reference to the key holder shown in Figs. 1 to 105 5 and to have inscribed, impressed or engraved thereon instructions for opening the holder and returning it the same as described with reference to Figs. 1 to 5 of the drawings. 110

For convenience in opening the case of the holder in either of the forms shown, a notch a^4 is cut in the margin of the outer overlapping flange co-incident with one of the flaps and open-ended slots in the flange 115 of the other member so as to provide a slit or opening in which the point of a knife blade may be inserted for prying it open. In the form shown in Figs. 1 to 5 both sides of the key holder are formed integrally 120 with their respective peripheral flanges, whereas in Figs. 6 to 10 one member, in this instance, the member B¹ is ring-shaped in form or has an opening in one side and a removable plate or cover b^4 placed over 125 said opening, said removable plate bearing the inscription which appears upon the corresponding side plate or disk member shown in Fig. 2, and the flap b^3 on the lower edge or periphery of the inner disk member is 130

utilized as a means for holding said removable plate in place against the inner wall of the member B¹, to prevent it from dropping out when the case is opened.

5 I thus provide a key holder that carries and makes available to the finder when lost a reward for its return to the owner, without requiring the finder to take the time required to call at any place for such reward, 10 as the coin or other medium of reward is contained within the holder itself, and all that the finder has to do is to open the holder, take out the reward and drop the holder in a mail box, or at his option take 15 it to the local bank whose name and address appears thereon. Furthermore, the key holder, by reason of the fact that it contains a coin of value as a reward to the finder, has also the merit of being a portable receptacle for such coin and to that extent prevents the person who carries the same from being entirely out of cash in the event of leaving home without sufficient funds at 20 hand for car fare or the like.

25 It will be understood, of course, that various changes may be made in the details and arrangement of parts without departing from the spirit and scope of my invention, for instance, the spring C may 30 be formed with but a single loop or with several loops properly spaced and projecting through a corresponding number of openings in the periphery of the case, and the device is susceptible of being used as 35 a tag or coin holder either with or without the key holding means, but with identifying means and instructions for returning the same to the owner in the manner hereinbefore described, and I therefore do not desire 40 to be limited in the appended claims to the specific construction and arrangement of parts shown and described.

Having thus described my invention, what I claim as new and desire to secure by Letters Patent is:

1. A key holder consisting of opposed disk-like members, each having a peripheral flange turned toward the other member; said flanges being adapted to fit snugly one with- 50 in the other for holding the two members together, and means carried by one of said members for attaching keys thereto.

2. A key holder comprising two disk-like members, each having a peripheral flange turned toward the other member; said flanges being adapted to fit snugly one within the other and hold the two members together, and a spring secured to one of said members, said spring having eyes or loops 55 formed thereon and protruding through openings in the peripheral flange of the spring-supporting member.

3. A combined key holder and coin container consisting of a pair of disk-like members each having a peripheral flange extend-

ing toward the other member; said flanges being adapted to fit one within the other for holding the two members together and forming a case for enclosing a coin or coins, one of said members having means projecting therefrom for attaching keys thereto. 70

4. A combined key holder and coin container consisting of two disk-like members, each having a peripheral flange turned toward the other member, said flanges being 75 adapted to fit closely one within the other for holding the two members together, a spring arranged within the peripheral flange of one of said members and having loops or eyes projecting therefrom through 80 suitable openings in said flange, said flange having inwardly turned flaps and said spring having end portions snapped under said flaps, whereby either end of the spring may be released for attaching a key or keys 85 thereto and again snapped under its retaining flap, and means for connecting said holder with a chain by which it may be suspended.

5. A combined key holder and coin container consisting of two disk-like members each having a marginal flange turned toward the other member; said flanges being adapted to fit one within the other for holding the two parts together; each flange having 90 an open-ended slot or slots therein registering with similar slots in the flange of the other member, one of said members having flaps formed by inwardly turned cut portions of its peripheral flange, and a 95 spring on the latter member having end portions snapped under said flaps and intermediate portions formed into loops or eyes which project through said registering slots.

6. A combined key holder and coin container consisting of two disk-like members each having a marginal flange turned toward the other member, said flanges being adapted to fit one within the other for holding the two parts together, each flange 100 having an open-ended slot or slots therein registering with similar slots in the flange of the other member, one of said members having flaps formed by inwardly turned cut portions of its peripheral flange, and a 105 spring carried by the latter member having end portions snapped under said flaps and intermediate portions formed into loops or eyes which project through said registering slots; one member having an oblong slot or 110

115 slot opening therein.

7. A key holder and coin or tag container comprising two disk-like members each having a peripheral flange turned toward the other member and an open ended slot or 120 slots in its peripheral flange registering with a similar slot in the other flange, that portion of the flange cut to form the slot in one member being turned inwardly to serve as 125 a means for holding a removable part with- 130

4
in the holder, one of said members having an oblong slot or sight opening therein to expose to view the owner's registry number enclosed within the holder.

5 8. As a means for inducing the finder of a lost article to return the same to the owner thereof, a coin and tag holder consisting of opposed members having overlapping peripheral flanges for securing them together 10 and a coin or coins and a tag or tags therebetween, a tag within the holder containing the instructions to enable the finder to return the device to its owner, and the holder bearing on its outer side or sides the name and address of a bank or other depository where the owner is registered and directions for opening the holder.

15 9. As a means for inducing the finder of a lost article to return the same to the owner thereof, a coin and tag holder consisting of 20

opposed members having overlapping peripheral flanges for securing them together and a coin or coins and a tag or tags therebetween, a tag within the holder containing the owner's registry number and instructions 25 to enable the finder to return the device to its owner, and the holder having in one side thereof a sight opening for viewing said registry number and bearing on its outer side or sides the name and address of a bank 30 or other depository where the owner is registered and directions for opening the holder.

In testimony whereof I affix my signature in the presence of two witnesses.

GEORGE R. PERRY.
